(57) **CLAIM**

The ornamental design for an organizational chart, substantially as shown and described.

DESCRIPTION

FIG. 1 is a top plan view of an organizational chart showing the new design; and,

FIG. 2 is a side elevational view thereof, all other sides being identical thereto.

The rear of the organizational chart according to the invention is plain and unornamented.

1 Claim, 1 Drawing Sheet

FIG. 1

FIG. 2
